DIRECTION SIGNAL

Everett R. Codde, Oakland, Calif.

Application May 24, 1939, Serial No. 275,545

1 Claim. (Cl. 177—329)

This invention relates to signals for motor vehicles and the like, to indicate a direction of travel and it consists in the constructions, arrangements and combinations herein described and claimed.

It is an object of the invention to provide a signalling means mounting in the vehicle top which is normally concealed, but projectable to a visible position through control means mounted on the steering wheel or other convenient position.

It is also an object of the invention to provide a novel means for projecting and retracting the signalling means as well as to provide a waterproof closure for the signalling means when in retracted operative position.

More specifically, it is an object of the invention to provide pneumatic means for projecting the signalling means and to simultaneously illuminate the signalling means.

Additional objects, advantages and features of invention will be apparent from the following description considered in conjunction with the accompanying drawings, wherein

Figure 1 is a side elevation of a motor vehicle having my signalling device installed.

Figure 2 is a front elevation thereof.

Figure 3 is a diagrammatic view of the wiring diagram for the signalling device.

Figure 4 is an enlarged cross section on the line 4—4 of Figure 1.

Figure 5 is a cross section on the line 5—5 of Figure 4.

Figure 6 is a view similar to Figure 4, enlarged, and illustrating the signalling device in operative position.

Figure 7 is a cross section on the line 7—7 of Figure 6.

There is illustrated a motor vehicle generally indicated at 10 having a top 11, the latter having a transversely extended well 12 formed therein adjacent each longitudinal edge and preferably medially of the length of the top.

The wells 12 are suitably built into the top to provide a waterproof joint, and preferably includes a drip channel 13 for conducting water away from the wells, so that the latter may be maintained dry. Each well 12 is identical in construction and a description of one will be ample for an understanding and operation of the signalling means now to be described, attention being directed particularly to Figure 4. A guide rod 14 is mounted between the base 15 and inwardly directed flange 16, a rod being provided adjacent respective ends of the well. Vertically

slidable upon the rods 14 there is a platform 17 for support of an illuminated indicator 18, this in the present instance being shown as an arrow, to indicate a proposed turn of the vehicle; as will be explained more fully hereinafter. The indicator 18 is supported by standards 19 at the ends thereof, the standards being rigidly connected to the platform and a closure plate 20, the latter being constructed to seat flush around the upper edges of the well 12. The indicator 18 may be additionally supported by rubber cushion blocks 21 arranged as shown. The indicator 18 is shown as a neon lamp embodying a pair of terminals 22 also suitably mounted in cushion blocks 23.

A stop lug 24 is fixed to each rod 14 limiting downward movement of the platform 17 and a fixed platform 25 is also supported by the rods 14, spaced a suitable distance above the base 15.

The platform 25 supports a transformer 26 having flexible conductors 27 for connection with respective terminals 22, the conductors being of such length as to permit full upward movement of the indicator 18. The platform 25 also supports a pair of bellows devices 28, the upper ends of the bellows being fixed to the underside of the platform 17.

Each of the bellows has an air inlet 29 connected to an air line 30, the latter being connected to an air control valve 31, attention being directed to Figure 6 for an understanding of the construction and operation of the valve. The valve 31 is suitably mounted in a compartment 32 adjacent one end of the well, the walls 33—34 being suitably apertured to admit an air inlet pipe 35, the pipe 36 and the exhaust pipe 38.

The valve 31 comprises a cylinder 37, closed by a screw plug 38 at the lower end, the upper end being closed by an insulated cap 39. The cap 39 has a pair of downwardly projecting contact members 40—41 being spaced apart to receive a contact 42 of a reciprocable piston 43. A helical spring 44 is interposed between the upper end of the piston and an inturned flange of the cylinder, the spring functioning to maintain the piston in its lowermost position.

A winding 45 is placed around the upper portion of the cylinder, having a lead 46 connected to one side of a switch 47, the other side of the switch being connected to a battery 48 by lead 49, it being understood that the winding 45 is grounded to the frame as indicated at 50. From the foregoing it will be understood that when the winding 45 is energized, the piston will be at

tracted upwardly, and this will be explained in greater detail hereinafter.

The piston 43 has a reduced portion 51 intermediate its length forming separate heads 52-53.

The air inlet 35 opens upon the cylinder 37 approximately medially of its length, and the pipe 38 opens upon the cylinder slightly below the inlet 35 so that when the device is in operative position, air may pass from pipe 35 into the cylinder and into the pipe 38 for discharge into respective bellows 28. The pipe 38 will open upon the cylinder at such point that the pipe 36 will be closed to the cylinder, by the head 52 when the piston is in raised operative position.

The operation will be readily understood from the following description. With the signal 18 in lowered position as shown in Figure 4, and it is desired to project the signal upwardly to a point of display as a warning to other vehicles, the desired switch 47 is actuated to close the circuit through lines 46 and 49, which in turn energizes the coil winding 45. When the coil is energized, the piston 43 will be drawn upwardly, engaging contacts 48 and 49, completing the circuit to the indicator 18 by way of the lead 54, the transformer 26 and the ground 55. When the piston 43 was raised, the port from the pipe 35 was uncovered, admitting air under pressure from a source 56. The air passes into the pipe 30 and thence passes into respective bellows 28 causing them to expand, raising the platform 17 with the indicator 18. The upward movement of the platform is limited as soon as the platform engages the flange 16. The switch 47 is held in operative engagement and as soon as released, the circuit will be broken, and when this occurs, the piston

43 will be forced downwardly by the spring 44, closing the port from the air line 35, and opening the port in the exhaust pipe 36. Thus the air in the bellows will be exhausted, allowing the indicator 18 to return to concealed position in the well. Such downward movement will be gradual, obviously, and damage to the indicator will be avoided. A vent 57 may be provided in the cylinder 31 to permit free downward movement of the piston.

While I have shown and described a preferred form of the device, this is by way of illustration only, and I consider as my own all such modifications in structure as fairly fall within the scope of the appended claim.

I claim:

In combination with a vehicle having a top, an elongated well formed in the top, a vertically expandible bellows housed in the well adjacent respective ends of the well, a platform carried by the upper portions of the bellows, vertical rods in the well cooperable with the platform for guiding the latter during movement thereof, stop means on the rods for limiting downward movement of the platform, upright rods on the platform, an illuminable indicator carried by the platform and supported by said last named rods, a cover fixed to the upper ends of the last named rods for closing the well when the bellows are in collapsed position, an electrical circuit for the indicator, pneumatic means for expanding the bellows, exhaust means for the bellows, and switch means operable by said pneumatic means for completing the circuit to the indicator means.
